ROLLER CHART

Melville E. Foster, Minneapolis, Minn.

Application May 6, 1948, Serial No. 25,440

1 Claim. (Cl. 242—107)

1

This invention relates to a chart roller assembly which is particularly adaptable for holding a rolled chart containing items of information such as stock listings in a stock room.

It is a general object of the invention to provide a simple, yet highly effective chart roller assembly to which an elongated chart can be readily attached and wherein the complete assembly can be conveniently supported on a vertical edge face or on the underside of a shelf in the stock room.

Another object of the invention is to provide a chart roller assembly which can be quickly and easily assembled and taken apart and wherein conveniently accessible means is provided for holding the assembly together and which is also adapted for readily adjusting the tension of a spring used to rewind the roller upon which the chart is mounted.

The above and other objects and advantages of the invention will more fully appear from the following description made in connection with the accompanying drawing wherein like reference characters refer to the same parts throughout the views, and, in which:

Figure 1 is a front elevational view of an embodiment of the invention mounted on the underside of a shelf;

Figure 2 is an enlarged rear elevational view, partially in section;

Figure 3 is an end elevation at the line 3—3 of Figure 2;

Figure 4 is a section taken approximately on the line 4—4 of Figure 2;

Figure 5 is an end elevation taken approximately at the line 5—5 of Figure 3; and

Figure 6 is an enlarged fragmentary detail of the crank structure.

The device includes a casing 7 having a top wall 8, a front wall 9 and end assemblies 10 and 11. The casing top 8 may be provided with suitable holes 12 through which attachment screws may be inserted. If desired, end brackets 13 having screw receiving openings 14 may be used so that the device can be secured to the edge of a shelf board.

The end assembly 11 is provided with an aperture 15 and the end assembly 10 is provided with a slot 16 which extends to the bottom edge of the end member and communicates with the open bottom portion of the casing 7.

Extending through the casing is a roller rod 17. It is shown extending through the aperture 15 in the end 11 for some distance. The other end of the rod 17 extends through the slot 16 in the end 10 and is bent over to form a crank arm 18. As best shown in Figure 6, the end of the crank arm

2

18 has a stud 19 extending therethrough. The inner end of the stud is enlarged and threaded as at 20 and the outer end of said stud is threaded as at 21 to receive a knurled head 22 which is tightly threaded on the stud 19. The stud is freely rotatable in the arm 18. The enlarged threaded portion 20 of the stud 19 is threaded into a threaded aperture 23 in the end 10. This holds the rod 17 in the inner end of the slot 16 as shown in Figures 2 and 3 and also prevents said rod 17 from turning relative to the casing 7.

Mounted on the rod 17 between the ends 10 and 11 is a roller 24 which is hollow and has a torsion spring 25 therein which lies about the rod 17. As viewed in Figure 2, the right-hand end 26 of the spring 25 is secured to the rod 17 and the left-hand end 27 of the spring 25 extends through the roller end 28 and is bent over so that it will be anchored securely.

20 A flexible chart 29 is shown in Figure 1. This may be of paper and be printed with listed information concerning articles of stock. The free end of the chart 29 is provided with a bar 30 which is of greater length than the open bottom portion of the casing 7 to provide a stop when the chart is wound upon the roller.

The chart has the other end thereof suitably secured to the roller 24 and while the chart and roller are held against rotation, the crank arm 30 18 is rotated after the threaded stud 19 has been detached from the casing end 10. This will cause the torsion spring 25 to be wound. When the desired tension has been placed upon the spring, the threaded stud 19 is threaded into the aperture 23 in the casing end 10. This will keep the spring under tension and it will also retain the rod 17 against displacement from the inner end of the slot 16 in the casing end 10.

40 When a chart is placed on the roller 24, the threaded stud 19 is released as described above and the rod 17 is slipped out of the slot 16. Then the other end of the rod can be slipped axially from the aperture 15 in the casing end 11.

45 The device is simple in construction and highly effective for compactly holding a relatively large roller chart. It does not take up any considerable amount of space such as is required for a large cardboard stock chart and consequently can be placed at any convenient position on a series of shelves. The casing 7 is provided with a front wall 9 which has a straight lower edge 31 which greatly facilitates reading across a line of printing on the chart 29. When the desired information has been secured in any instance, the spring

25 will rewind the chart, thereby keeping it out of the way when not actually being consulted.

It will, of course, be understood that various changes may be made in the form, details, arrangement and proportions of the various parts without departing from the scope of my invention.

What I claim is:

A chart roller assembly having in combination, a casing having first and second opposed end members and an open longitudinal portion, said first end member having an aperture therethrough to receive a roller rod, said second end member having a slot therein entrant from an edge thereof and communicating with said open longitudinal portion, a roller rod, a chart carrying roller rotatably mounted on said roller rod, a torsion spring connected at one end to said roller rod and at its other end to said roller, said rod having a first end projecting beyond one end of said roller and slidably removably receivable in the aperture in said first end member, and said rod having a second end projecting beyond the other end of said roller and radially slidable through said slot in said second end member, and cooperating releasable inter-engaging means car-

ried by the second end of said rod and said second end member, the part of said inter-engaging means carried by the second end of said rod being fixedly secured thereto and forming a handle 5 for turning said rod relative to said roller to tension said spring whereby the spring can be properly tensioned, said rod fixed from turning after said spring is tensioned, so arranged that the roller and rod can yet be removed when desired 10 from the casing.
